UNITED STATES PATENT OFFICE.

JOHN H. EARLES, OF DENVER, COLORADO.

CAR-COUPING.

SPECIFICATION forming part of Letters Patent No. 351,754, dated November 2, 1886.

Application filed August 21, 1886. Serial No. 211,543. (No model.)

To all whom it may concern:

Be it known that I, JOHN H. EARLES, a citizen of the United States, residing at Denver, in the county of Arapahoe and State of Colorado, have invented a new and useful Improvement 5 in Car-Couplings, of which the following is a specification.

My invention relates to improvements in car-couplings; and the object of my improvements is to provide a railway car-coupling which shall be simple, durable, practicable, and automatic. I attain this object by means of the mechanism illustrated in the accompanying drawings, in which—

15 Figure 1 is a side elevation of my improved device as the same would appear attached to the end of a car, the pin being down and the link in the draw-head. Fig. 2 is a side elevation of my improved coupling, showing the pin upraised. Fig. 3 is a top view of my coupling. Fig. 4 is a top view showing a longitudinal section of the draw-head. Fig. 5 is an elevated section of the draw-head, showing also the pin, trigger, and link, the link being 20 about to enter the draw-head. Fig. 6 is an edge view of the pin and trigger, the trigger being raised. Fig. 7 is a side view of the pin. Fig. 8 is a view of spring, by means of which the pin is kept raised, thus preventing the 25 coupling from acting when the link enters the draw-head.

In the drawings, *a a* are two levers, attached to the end of the car by bolts *a'* and clasps *a''*. Said bolts form the fulcrums of the levers. 35 The clasps are riveted or securely bolted to the car. Levers *a a* are of sufficient length to permit of their being operated without going between the cars. The inner extremities of levers *a a* contain the slots *a''*.

40 *b* is the pin, shaped as shown in the drawings. The upper extremity of pin *b* is provided with a lug, *b'*, containing a hole. The pin is attached to levers *a* by means of a bolt, *c*, which passes through the hole in lug *b'*, also 45 through the slots *a''* in levers *a*. Levers *a* also contain slots *a''*, as shown in Fig. 3. Slots *a''* are cut at right angles to slots *a''*. The manner of uniting the inner extremities of the levers when the pin is attached is shown in Fig. 3. 50 Slots *a''* are large enough, so that they move easily longitudinally upon bolt *c*. To the

lower portion of pin *b* is attached the trigger *d* by means of the rivet *d'*. Trigger *d'* moves easily upon the rivet.

e is the ordinary draw-head with some modifications. The hole *e'* is made larger, as the pin *b* is wider than the old-fashioned coupling-pins. The bottom of the inside portion of the draw-head is cut out so as to form a slight depression, *e''*. (Shown in Figs. 4 and 5.) The object of depression *e''* is to allow the inner extremity of the link to fall, so as to raise the outer extremity sufficiently for all practical purposes. This adjustment of the link is made by the use of levers *a*. The portion of the pin 65 marked *b''* rests upon the link when the pin is down. By raising the outer extremity of either lever *a* the inner extremity of the link is forced downward into depression *e''*. Pin *b* may also be adjusted from the top of car by use of a 70 suitable rod or lever. The lower extremity of the trigger when "set" rests in the rear portion of depression *e''*. The opening is sufficiently large to allow the trigger to revolve freely upon rivet *d'*.

f is a metal bar the extremities of which are bolted to the end of the car, the central portion being bowed up so as to leave a small space underneath, as shown in Fig. 8.

g is a spring, with the lower extremity turned 80 outward so as to form a hook, as shown. The upper extremity of spring *g* is riveted to bar *f*.

h is a movable slide or ring surrounding spring *g* and bar *f*, and may occupy any position on spring *g* below its fastening-rivet. 85 When slide *h* is near the lower extremity of the spring, as shown in the drawings, the spring is held close to the bar *f* throughout its length. It is held in this position when not in use. Its use is to hold the levers *a* in 90 such a position as to keep the pin *b* elevated when the link enters the draw-head, when it is not desired that the coupling should operate. The position of spring *g* when in use, and also of clasp *h* when the spring is in use, 95 is shown by dotted lines in Fig. 8. The levers *a* each contain a hole, *g'*, to receive the hooked extremity of spring *g*. The spring *g* is so placed that levers *a* must be forced down slightly in order that hook *g'* may enter the hole *g'*. This slight downward pressure elevates the pin sufficiently to allow the link to

enter the draw-head and pass out without resistance, the trigger simply swinging back and forth but not catching the link.

In the operation of my improved coupling 5 the pin *b* is raised by the use of levers *a* until the lower extremity of the trigger will rest in the rear portion of the depression *c* in bottom of the draw-head, standing with a slight inclination, as shown in Fig. 5. The pin *b* is raised 10 to in a vertical position by virtue of the slots *a*². The coupling is then ready for use. As the link enters the draw-head it causes the trigger *d* to turn upon its rivet *d*', as shown in Fig. 6. The pin then drops through the link, as shown 15 in Fig. 1, and the cars are coupled.

Having thus described my invention, what I claim, and desire to secure by Letters Patent, is—

1. In a car-coupling, the combination of levers *a*, attached to car by bolts *a*', which form 20 their fulcrums, said levers being provided with slots *a*², bolt *c*, pin *b*, trigger *d*, and a suitable draw-head, substantially as described, and for the purpose set forth.

2. In a car-coupling, the combination of levers *a*, provided with slots *a*² and *a*⁴ and holes *a*⁵, suitable fulcrums, *a*', bolt *c*, pin *b*, and a suitable draw-head, substantially as described. 25

3. In a car-coupling, levers *a*, provided with slots *a*² and holes *a*⁵, suitable fulcrums, *a*', bolt 30 *c*, pin *b*, a suitable draw-head, spring *g*, clasp *h*, and bar *f*, substantially as described.

JOHN H. EARLES.
